UNITED STATES PATENT OFFICE.

ORRIN J. SAVAGE AND GEORGE P. HAWLEY, OF ITHACA, NEW YORK.

IMPROVEMENT IN LAMP-BURNERS.

Specification forming part of Letters Patent No. 38,422, dated May 5, 1863.

To all whom it may concern:

Be it known that we, ORRIN J. SAVAGE and GEORGE P. HAWLEY, of the town of Ithaca, in the county of Tompkins and State of New York, have invented an Improved Lamp-Burner for Coal and other Similar Oils; and we do hereby declare that the following is a full and exact description thereof, reference being had to the accompanying drawings, and to the letters of reference marked thereon, in which—

Figure 1 is a perspective view of our burner, Fig. 2 is a perpendicular section thereof, and Figs. 3 are parts thereof.

In Fig. 1, A is the cone, perforated by slot through which the flame emerges, and B is a belt or zone of perforated sheet metal, and C is the base or lower member of the burner, and has a few large holes in it, and D is the shaft and knob of the wick-elevator. E is the screw by which the burner is attached to the lamp, and F is the wick.

In Fig. 2, A is a section of the cone, and B the belt, and C the base, and D the wick-elevator, and E is the screw, and F the wick, and G the wick holder.

In Figs. 3, A is the cone, and B the belt, making a large and expanded air-chamber between the cone and the base, and A x is the

slotted side of the cone, showing the wick-holder G in the slot.

The practical use of these parts of the burner is apparent to those skilled in the art to which it appertains. The lamp is lighted in the ordinary manner, and the effect of the several parts is such that the lamp can be carried or otherwise used without a chimney, for which purpose our combination and arrangement are made.

What we claim, and desire to secure by Letters Patent, is—

1. The cone A, with its slot narrowed at the top and gradually widening, by straight and uniform lines, to the bottom of the square or rectangular bottom, as represented.

2. The combination of the cone A, the broad and flaring finely-perforated or foraminous sheet-metal belt B, widening as it descends, and the base C, narrowing as it descends, with large perforations, made and used as represented and described, for the purposes set forth.

ORRIN J. SAVAGE,
GEORGE P. HAWLEY.
